UNITED STATES PATENT OFFICE.

EDWARD W. CARNES, OF CHICAGO, ILLINOIS, ASSIGNEE TO AMERICAN CAN COMPANY,
OF NEW YORK, N. Y., A CORPORATION OF NEW JERSEY.

TRIPLE-FRICTION-SEAT WALL-CAN.

1,196,082.

Specification of Letters Patent. Patented Aug. 29, 1916.

Application filed October 19, 1912. Serial No. 726,594.

To all whom it may concern:

Be it known that I, EDWARD W. CARNES a citizen of the United States, residing in Chicago, in the county of Cook and State of Illinois, have invented a new and useful Improvement in Triple-Friction-Seat Wall-Cans, of which the following is a specification.

This invention relates to a triple friction seat wall can and it consists in a triple friction seat closure made in a peculiar manner hereinafter more fully set forth and claimed.

In the accompanying drawing, which forms a part of this specification, Figure 1 is a section of a can provided with the improved closure of this invention; Fig. 2 is a fragmentary section of the cover, and Fig. 3 is a fragmentary section of the can, upon a somewhat enlarged scale to show the construction more clearly.

In the said drawing the can body is marked 10, and is of the ordinary construction of sheet metal cans of the so called sanitary type, the can top being of the annular wide-mouthed sort and made with a flange 11, to interfold or double seam with the upper edge of the body as shown. Within this interfolded flange the annular can top is formed with a downwardly projecting wall, 12, fitting snugly within the wall of the can body. This vertical wall 12 is stiffened by the horizontal ring 13 from the inner edge of which rises the wall 14 terminating in the substantially horizontal stiffening ring 15, from the inner edge of which depends a second wall 16 terminating below in the second substantially horizontal stiffening ring 17 from the inner edge of which rises a short free edge 18. The configuration of the can top, it will be seen, therefore may be said to consist of four substantially vertical walls, the inner one of which has a free edge, a horizontal flange for double seaming with the can body and three horizontal stiffening rings. The counteracting cover 19, adapted to fit upon this configuration is made with the horizontal stiffening plate or part 20, from the outer edge of which depends the wall

21, terminating below in the horizontal strengthening ring 22, from the outer edge 50 of which ring rises the wall 23, terminating above in the horizontal strengthening ring 24 from the outer edge of which depends the free edge 25. Between the ring 24 and the free edge 25 the corner is preferably double 55 to form an annular projection 26 to serve as a shoulder against which the end of a lever for prying open the can by lifting the cover on the edge of the can as a fulcrum, may be seated. It will be seen that the configuration of the cover counters that of the can top and may be said to consist of three substantially vertical walls, the outer one of which has a free edge, a central strengthening plate, two horizontal stiffening rings 65 and a doubled projection forming a pry-off rim to receive an opening tool.

Where the accurate mathematical terms vertical and horizontal are made use of in the foregoing description it is not meant 70 that these parts need be precisely vertical or horizontal.

To apply the cover the parts are placed together in the position shown in Fig. 1 of the drawing, the cover being pressed down 75 to engage the can top. It will be seen that when so brought together the can-top and its cover engage each other in three separate frictional seats, one seat being between two walls stiffened both above and below by horizontal stiffening rings and two seats being 80 between free edges respectively of the cover and can top and stiffened walls respectively of the can-top and cover. The result is a tight and purely frictional closure that will 85 resist great internal gaseous pressure producing a can that may be used for many purposes for which it has heretofore been thought essential to employ vessels sealed by solder or by packed joints. 90

I claim:

A triple friction seat wall closure for cans, consisting of a can body formed with an inner upwardly extending and inwardly inclined flange with a free upper edge and having an 95 outside friction seat wall, an outer wall in-

wardly inclined and having an outside friction seat wall, and an intermediate wall, outwardly inclined and having an inside friction seat wall; and a cover having three friction seat walls adapted to conform with said seat walls of the can body, the outer seat wall of said cover terminating in a free bot-

tom edge and its inner seat wall terminating at its top in a can-closing stiffening plate.

EDWARD W. CARNES.
